CAN OPENER

Application filed February 11, 1928. Serial No. 253,589.

This invention relates to a device for opening cans by cutting the can end adjacent its juncture with the side wall. Tin cans are commonly constructed with the ends secured to the body by a flange or bead overhanging the side wall. The present invention appertains to a can opener having a knife blade which is caused to penetrate the end and to cut by being drawn along the line of desired severance. Advance of the knife is effected by a traction wheel engaging the underside of the bead.

The objects of this invention are first, to provide a tool of the character described having arms movable to and from each other, one of said arms carrying a knife blade and the other a traction wheel; second, to provide means for locking the arms with the knife blade in cutting position; third, to provide means to hold the traction wheel in driving engagement with the bead; fourth, to so position the blade and traction wheel as to maintain the side wall outer edge of the can between the wheel and blade and thereby avoid displacement; fifth, to provide a blade which acts by shearing the can end; and sixth, to provide details of structure whereby a simple, compact easily manipulated can opener, positive in operation, durable and economical to manufacture is obtained.

Other objects and advantages will be fully apparent from the following specification considered in connection with the accompanying drawings, in which:

Fig. 1 is a side elevation of a can opener embodying the invention in open position; Fig. 2 is a side view showing the opener applied to a can and locked thereto; Fig. 3 is a section as seen on the line 3-3 of Fig. 2; Fig. 4 is a plan view; Fig. 5 is an elevation from the opposite side to that of Fig. 2 showing a fragment of the cutting end; and Fig. 6 is a section as seen on the broken line 6-6 of Fig. 5. Referring with more particularity to the drawings, 10 and 11 indicate arms in the form of handles secured together by a pivot pin 12 so that the arms may be swung to and from each other. Intermediate the ends of handle 10 is a knife

blade 13. The knife blade is shown herein as being detachable and secured to the blade by a screw 14. It is offset as indicated by 15 so as to position the blade in the plane of the handle. The shearing edge is inclined as indicated by 16. This edge may be comparatively blunt.

Handle 11 is provided with a guide 17 to overlap the handle 10 and maintain the handles against lateral displacement. Preferably formed integral with the handle 11 and offset therefrom is a bracket 18 providing a shoulder 19 which is slotted at 20 for the passage of the knife blade therethrough. The bracket extends downwardly at a slight inclination outward from the plane of handle 11. There is an inwardly extending foot or projection 21 at the end of the bracket.

Journalled in the bracket 18 is a shaft 22 having fixed thereto a traction wheel 23. On the shaft is a collar 24 to prevent longitudinal displacement of the shaft 22. Secured to the shaft is an operating wing member 25 for driving the traction wheel. It will be noted that the planes of the knife blade and traction wheel are offset from one another and when in closed or near position of the handles, the blade overlaps the driving wheel.

The can opener shown is of the portable type, but it will be understood that the invention is not limited to a portable can opener. In the beginning of operation, the handles are open or in far position as shown in Fig. 1, the end of the blade 13 being spaced from the periphery of the traction wheel 23. The opener is then positioned with the bracket 18 along side of the side wall 26 of a can, the foot 21 engaging the can and with the bead 27 disposed above the traction wheel so that the teeth thereon will engage the underside of the bead. The knife blade 13 overhangs the bead inwardly and above the can top 28. Next the handles are closed, causing the blade 13 to penetrate the can top on the inside of the bead and the traction wheel to press against the underside of the bead on the outside of the can. In closed position the side wall of the can at its

end is disposed between the overlapping blade and traction wheel and the can opener is held against lateral displacement. By holding the handle in closed position and turning the driving member, the can opener will be advanced with respect to the can, drawing the knife blade along the top and causing a shearing cut by the inclined edge 16 of the blade. It will be understood that to advance the blade in the proper direction, the driving member must be turned in a right hand direction in accordance with the opener illustrated.

In order to maintain the handle closed and locked to the can without further attention of the operator in this respect, we have provided a lock. Mounted upon handle 11 is a leaf spring 29 secured to the handle at one end. Secured to the leaf spring is a pin 31 operating in an aperture in the handle for engaging a recess 32 in the other handle 10. The leaf spring tends to maintain the pin in the recess 32 when the pin and recess are registered. The result is that when the handles are brought together in closed position, the pin and recess registering, the pin will be caused to position itself in the recess and lock the handles together, the spring holding them in this position. In order to release the handle, a thumb piece 33 is secured to the end of the spring member and is so fulcrumed upon the handles, that by pressure upon the thumb piece the pin will be lifted from the recess. It is within the scope of the invention to employ any suitable locking means.

A bowed leaf spring 34 secured at one end to the handle 11 at the bracket and engaging at its free end the handle 10 tends to open the handles. This spring also serves another function, that of resiliently holding the traction wheel against the bead by pressing downwardly upon the can end. It will be noted that as the handles are closed the spring is pressed toward the traction wheel. When the handles are not in closed position the spring acts to maintain the traction driving relation between the traction wheel 23 and the bead of can 27. When the opener and can are moved in cutting operation spring 34 frictionally slides along the can end. Assuming that the handles are open, the can opener is applied to the can as before described and the handles swung to closed position. When the handles have reached their near or closed position, the lock operates to maintain the handles closed. At the same time the spring 34 presses downwardly upon the top of the can to maintain the traction wheel against the bead. The driving member is now turned in the right hand direction. In operating the can opener it may be found convenient to hold the opener after it has been locked in place and allow the can to be turned. Turning of the driv-

ing member will cause the can to turn in relation to the opener, and the knife blade will shear the can end 28, completely severing the same. Due to the shearing action and inclination of the blade edge 16 there is a tendency to tilt the top and when cutting has been about completed, the severed end is tilted upwardly so that it can be grasped and lifted from the can rather than falling into the can where it is comparatively inaccessible.

What we claim is:—

1. A can opener comprising a pair of lever arms movable to and from each other, a knife blade on one of said arms for penetrating and cutting a can end, a traction wheel on the other arm disposed in a plane offset from the plane of said blade for engaging the underside of a can bead, a catch to lock said arms together with said wheel and blade in near position, resilient means on one of said arms opposite to said wheel to frictionally press said wheel against the underside of said bead when said arms are locked in near position, and means to drive said wheel.

2. A can opener comprising a pair of handles pivotally connected so as to be swung to and from each other, a knife blade on one of said handles for penetrating and cutting a can end, a traction wheel on the other handle disposed in a plane offset from the plane of said blade for engaging the underside of a can bead, resilient means on one of said arms facing said wheel to frictionally press said wheel against the underside of said bead when said arms are in near position, and means to drive said wheel.

3. A can opener comprising a pair of lever arms movable to and from each other, a knife blade on one of said arms for penetrating and cutting a can end, a traction wheel on the other arm disposed in a plane offset from the plane of said blade for engaging the underside of a can bead and disposed with relation to said blade so as to overlap the latter when said arms are in near position, means to lock said arms together with said wheel and blade in near position, yieldable means for bearing against the can opposite to said wheel to frictionally press said wheel against the underside of said bead when said arms are in near position, and means to drive said wheel.

4. A can opener comprising a pair of handles pivotally connected so as to be swung to and from each other, a knife blade on one of said handles for penetrating and cutting a can end, a traction wheel on the other handle disposed in a plane offset from the plane of said blade for engaging the underside of a can bead and disposed with relation to said blade so as to overlap the latter when said handles are in near position, means to lock said handles together

with said wheel and blade in near position, means opposed to and facing said wheel to resiliently press said wheel against the underside of said bead when said arms are in near position, and means to drive said wheel.

5. A can opener comprising a pair of lever arms movable to and from each other, a knife blade having an inclined advance edge for shearing a can end on one of said arms, a traction wheel on the other arm disposed in a plane offset from the plane of said blade for engaging the underside of a can bead, a leaf spring on the arm carrying said wheel and facing the latter to press said wheel against the under side of said bead, and means to drive said traction wheel.

6. A can opener comprising handles pivotally joined so as to be swung to and from each other, a knife blade projecting inwardly from one of said handles, an offset bracket on the other of said handles having a ledge in alignment with said blade and an opening for the passage of the blade therethrough, a traction wheel journaled on said bracket with its plane offset from the plane of said blade, means to drive said wheel a bowed spring can engaging member disposed on the handle carrying said traction wheel for resiliently pressing against the can end and holding said wheel in driving relation with the underside of the can bead, means to lock said handles together in near position, and means to drive said wheel.

7. A can opener comprising a pair of lever arms movable to and from each other, a blade for cutting a can end on one arm, a traction wheel on the other arm in a plane offset from the plane of said blade for engaging the underside of a can bead, a leaf spring mounted on the arm carrying said wheel and facing the latter to press said wheel against the under side of said bead, the free end of said spring engaging the arm carrying said blade so as to be pressed toward said wheel on closing movement of said arms, and means to drive said traction wheel.

50 In witness that we claim the foregoing we have hereunto subscribed our names this 31st day of January, 1928.

CALEB COTTEN.
ISRAEL P. DUNCAN.
